CLAIM

The ornamental design for a cup sleeve element, as shown and described.

DESCRIPTION

FIG. 1 is a top, front perspective view of a cup sleeve element of the present invention shown in the cup sleeve configuration and applied to a cup;

FIG. 2 is a front elevation view thereof;

FIG. 3 is a top, front perspective view thereof, shown in the cup sleeve configuration;

FIG. 4 is a top, front, right side perspective view of the cup sleeve element of the present invention;

FIG. 5 is a top, rear right side perspective view thereof;

FIG. 6 is a front elevation view thereof;

FIG. 7 is a right side elevation view thereof, the left side elevation view being a mirror image;

FIG. 8 is a rear elevation view thereof; and,

FIG. 9 is a top plan view thereof, the bottom plan view being a mirror image.

The broken lines in the drawings showing the additional cup sleeve elements, the cup and the elastic elements in FIGS. 1, 2 & 3 are for illustrative purposes only and form no part of the claimed design. The broken lines in the drawings showing a portion of the front surface of the cup sleeve element in FIGS. 1-4 & 6 illustrate the portions of the design that form no part of the claim.
